UNITED STATES PATENT OFFICE.

LEEDHAM BINNS, OF PHILADELPHIA, PENNSYLVANIA.

THREAD-GUARD FOR CAP SPINNING AND TWISTING MACHINES.

SPECIFICATION forming part of Letters Patent No. 359,007, dated March 8, 1887.

Application filed November 24, 1886. Serial No. 219,763. (No model.)

To all whom it may concern:

Be it known that I, LEEDHAM BINNS, of Philadelphia, in the county of Philadelphia and State of Pennsylvania, have invented new and 5 useful Improvements in Thread Guards for Cap Spinning and Twisting Machines, of which the following is a full, clear, and exact description.

This invention relates to the guards used in 10 cap spinning and twisting frames to prevent the several yarns from interfering or entangling with each other when being spun and twisted.

The invention consists in a novel construction of the guards, of partly circular form at their backs and of a peculiar shape at their front edges; also, in a combination of the 15 guards, made to interlock with one another at their front edges, and the back board, top 20 board, and caps and spindles of the frame or machine, substantially as hereinafter described.

Reference is to be had to the accompanying drawings, forming a part of this specification, in which similar letters of reference indicate 25 corresponding parts in all the figures.

Figure 1 represents a mainly sectional side view only of so much of a cap spinning and twisting frame as is necessary to illustrate my invention, the same showing but a single spindle and cap with parts immediately pertaining thereto and with my improved guard applied. Fig. 2 is a partially-sectional plan view showing the back board of the machine and a pair of my improved guards applied to 30 a couple of caps and their spindles. Fig. 3 is a front elevation of one of the guards detached.

A indicates the back board of a cap spinning and twisting frame or machine, and B the usual top board thereof.

40 C is one of the top rollers, and D one of the bottom rollers, between which and down through an eye in the top board each yarn b passes to its respective spindle c, or bobbin d thereon.

45 E is the spindle-cap; e the whirl by which the whirl-tube e' is rotated upon the fixed spindle e. f is the traversing-rail, and g the foot or spindle rail, all as in other cap spinning and twisting frames.

50 G G are the guards between the caps E. These guards run up to the under side of the top board, B, and extend to the bottom of or a

little below the caps, or thereabout, as usual. Said guards, which may be made out of sheet metal, are bent or shaped so that they assume 55 in horizontal or transverse section a partly-circular form, corresponding to or approximating a half-circle, concave on their inside at their backs h; and in some cases I make their tops i of a partial bell or dome shape, 60 thereby entirely dispensing with all angular nooks and corners, and allowing the yarn to travel perfectly at ease and so that as it is rotated it will only once at each revolution strike the guard or guards on what may be called the 65 "going-on" side—that is, on the left or right hand side, accordingly as the yarn is being spun or being twisted or doubled—instead of striking on the sides of adjacent guards and inner surface of the back board. This reduction in the striking of the yarn enables the latter to be twisted more perfectly and steadier, and the yarn coming in contact with the interior curved surface of the guard has its outside fibers rolled onto it instead of being battered, thereby causing less waste and making 70 a smoother or polished yarn. No awkward corners or angular spaces are left within the guards or between them and the back board or top board for the collection of hairs, fuzz, 75 or waste; but the guards may be quickly wiped out by rubbing a cloth up and down within them, if necessary, at distant periods of time, to remove any such material as may be left there, instead of having to frequently pick it 80 out of angular spaces between the guards, back board, and top board. This will greatly economize labor and there will be less waste.

The guards G may be fastened to the back board, A, by a single row of screws, s, arranged 90 centrally down the back of them. Their forward vertical edges, which stand out in front on opposite sides of the cap, are constructed so that the one edge, k, is plain and straight, while the other edge, l, is turned over to form 95 a lap or pocket for the plain straight edge k of the next guard to engage and fit within, after the fashion of a tongue-and-groove joint. This construction provides for the several guards throughout the whole row of spindles, or for 100 any number of them, supporting one another in front, thus making them solid or substantial in front as well as at their backs, instead of, as in the case of the ordinary double guards,

depending upon wings to hold them at their backs and leaving them loose or free in front, and consequently liable to get out of position.

Having thus described my invention, what I claim as new, and desire to secure by Letters Patent, is—

1. The within-described guard for cap spinning and twisting frames, of partly circular construction at its back *h*, and having a straight front edge, *k*, on one side and a turned-over front edge, *l*, on its opposite side, substantially as specified.

2. The combination, in a cap spinning and twisting frame, of a series of guards, *G*, having curved backs continuous with their sides and made to interlock with one another by tongue-and-groove joint down their front edges, the back board, *A*, to which said guards are secured in their rear, the top board, *B*, the caps *E*, and spindles *e*, essentially as described.

LEEDHAM BINNS.
